(57) **CLAIM**

I claim the ornamental design for a planter, as shown and
described.

DESCRIPTION

FIG. 1 is an isometric view of the design;

FIG. 2 is a front elevational view of the design;

FIG. 3 is a side elevational view of the design;

FIG. 4 is a top plan view of the design;

FIG. 5 is a bottom plan view of the design;

FIG. 6 is a perspective view of the design;

FIG. 7 is an exploded view of the design; and,

FIG. 8 is a perspective view of one half of the claimed
design shown in the exploded view of FIG. 7.

The broken lines in the figures depict portions of the planter
that form no part of the claimed design. The broken lines in
the figures showing plants and a mailbox illustrate environmental
structure and form no part of the claimed design.
The right side elevational view of the design is a mirror
image of the left side. The front side elevational view of the
design is a mirror image of the rear side.
